UNITED STATES PATENT OFFICE.

EGBERT S. BROWN, OF NEW YORK, N. Y.

CARRIER.

Application filed January 3, 1921, Serial No. 434,846. Renewed June 29, 1923.

To all whom it may concern:

Be it known that I, EGBERT S. BROWN, a citizen of the United States, residing at New York, in the county of New York and State 5 of New York, have invented new and useful Improvements in Carriers, of which the following is a specification.

This invention relates to carriers.

More particularly the invention relates to 10 carriers embodying traction means for translating goods, wares and merchandise. Some of the objects of the present invention are: to produce a device of the character mentioned which will embody a loop 15 formed principally from an element possessing inherent flexibility by virtue of which the loop may be decreased or increased in size according as it is subjected to or relieved from the weight of the thing 20 to be translated; to produce a simple and thoroughly efficient device which embodies parts which automatically grip and release a thing; to provide means for limiting the said loop to a predetermined size; to form 25 the said loop with relatively different degrees of flexibility so as to facilitate the decrease and increase thereof. With these and other objects in view the invention resides in the particular provision and construction of parts hereinafter more fully described and illustrated in the accompanying drawing, in which:

Figure 1 is a perspective view illustrating the device of the present invention in use.

Figure 2 is a central longitudinal sectional view.

Figure 3 is a transverse detail sectional view taken on the line 3—3, Figure 2.

Referring now more particularly to the 40 drawing for the details of construction of the device of the present invention it will be manifest that, the same includes, principally, an element 10 having connected thereto at one end, traction means 11, and a connector 12 at the opposite end thereof. The element 10 is composite in nature and consists of a strand of inelastic but flexible material 13, and a plurality of volute members 14, 15 and 16, which are arranged telescopically on the strand 13. The members 14, 15 and 16 are of different diameters. The member 14 is substantially equal to the length of the strand 13; the member 15 is substantially two-thirds the length of member 14; and the member 16 is substantially one-third the length of member 15. When

the said members are arranged telescopically with relation to each other about the strand 13, they constitute an element of relatively different degrees of flexibility, the purpose 60 of which will appear.

In order that the element 10 may be formed into a loop, the connector 12 is made to surround a portion of the element. The connector 12 comprises plates 17 which are 65 held in spaced relation by portions thereof which are inturned as at 18, and the end of the element 10 which is brazed, soldered or otherwise secured between the said plates 17. The inturned portions 18 and a curved member 19 which will be disposed on opposite sides of the element 10 serve to overcome friction considerably.

The end of the element 10 to which the part 12 is connected is relatively stiff, inasmuch as the said end, cross-sectionally, consists of the strand 13, and the three members 14, 15 and 16. Under such arrangement the loop may be quickly decreased and quickly increased to its normal size from the decreased size.

The connector 12 embodies jaws 20, 20, which, when the loop is reduced to a carrying condition, grip the thing to be carried. The end 21 of the member 16 serves as a 75 stop. The said end engages the jaws 20, 20, and thus limits the reduction of the loop to a predetermined size, and prevents unnecessary strain from the weight of the thing being carried from destroying the flexibility of the element.

The traction means 11 consists of a part 22 which supports a grooved wheel 23 operable over a track. The traction means 11 may be dispensed with if desired. The traction means 11 is useful when things are to be translated from one point to another, whereas, without the traction means 11, the device may be used for hanging things such as bananas on the spike.

The device of the present invention is highly effective for translating bananas on the spike or stem. In practice, the upper end of the stem is extended or projected into the loop formed. By allowing the weight 105 of the stem and the fruit thereon to play against the bight of the loop, the same will be quickly decreased or reduced in size until the jaws 20, 20, grip the said stem. The grip is most effective and allows the bananas to be readily translated to any desired place. When the device is relieved of the

weight of the fruit, the inherent flexibility of the loop, causes the loop to automatically enlarge itself for the ready removal of the fruit as will be understood.

5. It is to be understood that no limitations are made to the precise details of construction disclosed, but that changes, alterations and modifications within the scope of the claims may be resorted to when they are 10 deemed desirable and necessary.

What is claimed is:

1. A device as characterized embodying an element formed into a loop, the said element comprising a plurality of telescopically arranged volute members being flexible to allow the decrease and subsequent automatic increase of the said loop, and traction means. 15

2. A device as characterized embodying an element formed into a loop, the said element comprising a plurality of telescopically arranged volute members having different degrees of flexibility to allow the decrease and subsequent automatic increase of 20 the said loop.

3. A device as characterized embodying a composite element adapted to be formed into a loop, means for holding the element in loop formation, the said element comprising a plurality of telescopically arranged volute members being flexible, the said means allowing the loop to be decreased and subsequently automatically increased under the 30 action of the flexibility of the said element.

35. 4. A device as characterized embodying

an element formed into a loop, the said element comprising a non-elastic flexible strand; and volute flexible members surrounding the strand in telescopic relation.

5. A device as characterized comprising 40 traction means, a composite element including a plurality of volute members of varying degrees of flexibility connected to said means, and means for maintaining the element in looped formation. 45

6. A device as characterized comprising traction means, a composite flexible element adapted to be formed into a loop connected to said means, and means including spaced plates and guide members for maintaining 50 the element in looped formation.

7. A device as characterized comprising traction means, a composite flexible element adapted to be formed into a loop connected to said means, means for maintaining the element in looped formation, and means for limiting the reduction of the loop to a predetermined size. 55

8. A device as characterized comprising traction means, a composite flexible element 60 adapted to be formed into a loop connected to said means, slideable means including jaws for maintaining the element in looped formation, and a stop on said element which coacts with said jaws for limiting the reduction of the loop to a predetermined size. 65

In testimony whereof I hereby affix my signature.

EGBERT S. BROWN.
